UNITED STATES PATENT OFFICE

JOHN B. ADLER, OF AURORA, ILLINOIS, ASSIGNOR, BY MESNE ASSIGNMENTS, TO LYON METAL PRODUCTS, INCORPORATED, OF AURORA, ILLINOIS, A CORPORATION OF ILLINOIS

FOLDING CHAIR

Application filed May 25, 1927. Serial No. 194,204.

My invention relates to folding chairs, particularly those composed in whole or in part of metal, and the general object of the invention is to provide a chair of this type which shall be rugged, durable, attractive in appearance and comparatively cheap to manufacture. Another object is to provide a construction such that when the chair is folded it will maintain itself in that condition unless an appreciable force is applied to it to put it in erect condition, that is, in condition for use. This characteristic is accomplished, generally speaking, by making certain of the parts slightly resilient, and so constructing and arranging the parts in general that as the seat moves up to folded position it will move past the dead center and hence be retained in such folded position.

Another object is to provide a chair of this character which in being changed from folded to erect condition will automatically lock itself in erect condition, thus avoiding the possibility of the chair collapsing while in use or in case it comes into contact with external objects in being moved around. A still further object is to obtain great rigidity when the chair is erect, thus affording a sense of substantiality and firmness when in use.

Other objects and improved structural features will be referred to at length in the following description and particularly pointed out in the subjoined claims, reference being made to the accompanying drawings in which a practical embodiment of the invention is illustrated.

In said drawings Figure 1 is a perspective view of my improved chair, set up for use.

Figure 2 is an enlarged view in front elevation of the chair with the seat folded.

Figure 3 is an enlarged detail view of one of the seat pivots taken on the line 3-3 Figure 2 and looking in the direction of the arrows.

Figure 4 is an enlarged perspective view of a portion of the seat showing the seat catch or lock.

Figure 5 is a side elevation of the chair chiefly in section, showing the chair in erect or acting position.

Figure 6 is a vertical section of the chair

with the seat folded, the view being taken on the line 6-6 of Figure 2.

Figure 7 is a skeleton view in side elevation showing the relative positions of the collapsible parts of the chair when the seat is folded; and

Figure 8 is a similar view with the same parts about to be projected into erect or extended position.

In the preferred embodiment shown, the back of the chair and the back legs are composed principally of a single tubular member of approximately inverted U-shape extending from top to bottom of the chair. This results in the formation of a back frame 65 1 located above the seat 4 and a pair of back legs 2 extending from the seat down to the floor. The back legs 2 are practically straight from floor rests to the locality of the pivots for the seat and from this point they 70 extend rearward and inward of the seat to a point where they are again slightly bent to project approximately upright with just enough incline to make a comfortable back rest.

A curved back plate 5, preferably metal, is spot welded or otherwise suitably fixed to the back frame adjacent the rounded top thereof, a space being left between the frame top and plate 5 to provide a hand grip around 80 the top for handling the chair. The bottom edge of the plate is also curved to correspond substantially with the curvature of the front of the seat.

The single front leg 3 is constructed preferably of the same material as the back legs and has a forked upper extension 6, the two rearward branching parts thereof having their extremities flattened out and provided with bolt or the like holes so as to hingedly 90 connect the front leg to the under side of the seat 4 at the front edge thereof. For this purpose L-shaped straps or the like 7 are secured in spaced relation to the under side of the seat with one of their angular faces depending downward and also having openings through which bolts or the like may pass for connecting the leg.

The seat construction includes a cushion, leather as an example, the upholstery of 100

which is securely fixed in the nesting parts of the frame 8, which are joined by small bolts, rivets, screws or the like. The construction of the seat per se is only briefly referred to here since it has little to do with the existing novelty so far as this particular case is concerned. It should be noted, however, that the inner nesting part 9 has a cover piece, preferably of sheet metal like the other parts of the seat frame, which provides an anchoring surface for the L-shaped strap hangers 7 as well as other attachments to be hereinafter described. I also wish to point out that the shape of the seat blends in with the general design. The modified cone-like shape thereof also corresponds with the general outline of the space between the side members of the back rest below the plate 5. As shown to best advantage in Figures 2 and 6 the seat when folded is all but contained in this space. The seat is hinged or pivoted between the back legs just below the first bend therein. A connection suitable for this purpose may be constructed by welding a U-strap or channel piece 10 to the inside of each of the back legs with its cross piece adapted to lie parallel with the side of the seat frame and having an opening therein for the reception of a bolt or the like 11 projecting through the seat frame. The parts 10 space the seat from the inside of the back legs so that the sides of the seat can be folded in the space between the back frame.

Secured to the nested part 9 under the seat and extending from front to back centrally thereof is a slotted channel track 12 having outwardly presented attaching flanges flat against the plate of the nested top. Confined in the channel of this track is a slideable block 13 having depending portions projecting through the groove to provide a pivot mounting 14 at one end and a barb-like tooth 15 at its opposite end. Hingedly anchored to the pivot mounting 14 on the sliding block is an oblique channelled brace 16 for the seat. Its hinged connection with the pivot mounting is effected by cutting away the metal intermediate the angular faces thereof to provide a recess for the reception of the mounting part 14 and with registering openings in the angular faces registering with an opening in the part 14 and through which a bolt is passed. The recess in the channel of this brace is faced forward, the purpose of which will be presently described, and the opposite or lower end of the brace is pivoted at 25 to a small upstanding boss 18 between the extremities of the arched back leg brace 19. The pivoted connection at this end of the brace 16 is made in practically the same manner as at the opposite end. It should be noted that the brace is deflected from a straight line between its ends, preferably by a bend 17. The bend 17 in the brace enables the body thereof to clear the edge of the seat

frame when the seat is folded. Attention is also called to the fact that this bend is formed to meet the edge of the seat frame when the parts are folded. Also pivotally secured to the leg brace 19 immediately below the oblique brace 16 and with its connection made to a boss at right angles to the boss 18 is a horizontal brace 20. This particular brace is also a channel-like member but with its recess presented downward. It is connected at its forward end to the front leg 3 by a bifurcated pivotal connection 22. A bend 21 or other suitable deflection is made in this brace also.

Considering that the chair is folded with the seat up against the back as shown in Figure 6, any one desiring to extend the seat may grasp the back at the top thereof with one hand and then with the other hand impart a downward and outward thrust to the front part of the seat and continue to move the same to the limit of its extended position. As the seat moves forward the block 13 will slide forward in the track 12 until it comes to rest adjacent the front end of the track. At this stage it will trip and ride under the pivoted latch 23 and automatically interlock therewith under the influence of the spring 24 to hold the seat down. This latch may be conveniently made as a one-piece stamping having attaching ears between its ends which straddle the track 12 with a pivotal connection therewith. A lip is provided on the latch for engaging the barb on the block. The actuating end of the latch terminates adjacent the forward edge of the seat so that anyone grasping the edge of the seat at the most convenient locality to raise the same may conveniently use a finger to press the latch and release the slide. The latch is positioned between the forks of the front leg, and it acts as a guide for the hand to the extent that if the seat is gripped between the forks one or more fingers will surely rest upon the latch. The latch is thus automatically operated for all practical purposes. Being under the seat and located as described it is concealed, which is desirable, yet easily located. Another advantage in having the latch located in the position described is that the seat must be gripped at a point which happens to be a location that gives maximum leverage in the act of raising the seat.

The foregoing describes the construction of the chair parts and their assembly. However, their cooperative relationship, the relative positions of the pivot points and the distribution of forces transmitted from one part to another are also important features. In this connection I wish to call particular attention to the nesting of the front leg 3 in the recess of the horizontal brace 20 when the seat is folded, and the nesting of the brace 20 in the recess of the oblique brace 16. These

three parts move into and out of folded position in the same plane, the pivot points for the rear ends of the braces are fixed, and the pivot points for their forward ends are movable from a projected position in advance of the rear ends to a position in substantially the same vertical plane.

The sliding connection for the brace 16 in the channeled track permits a free folding action of the seat, but just before the seat moves into its arrested folded position the block arrives at the end of its sliding movement and is arrested at the rear end of the channel. Further movement of the seat at this time to complete the folding action imposes a decided pull on the brace 16 with the result that the arched brace 19 pulls the back legs 2 together, as shown in full lines in Figure 2. When the seat is folded past the position in which the pivot 24 lies in the plane defined by the seat pivots 11 and the brace pivot 25, that is to say, past a dead center position of the seat with respect to the frame, the tensional pull on the brace 16 due to the legs being drawn together holds the seat folded behind the dead center position, under tension against the stop between the bend 17 on the brace 16 and the edge of the seat. The seat is thus folded into a position with the brace 16 across the dead center which it cannot move out of except by imparting a decided forward thrust thereto. Accidental or unintentional lowering of the seat will therefore be avoided.

This action is well represented in Figures 7 and 8. For instance, in Figure 8 the movement of the sliding block has already been arrested and the spaced angular position of the three pivot points shows the oblique brace pivot on the brace 19 in a position that it would assume when the seat is extended which is below the horizontal plane that intersects its center when the seat is folded. In other words the brace 19 flexes and the legs 2 draw together to permit the seat to fold past the dead center of the brace pivots 24 and 25. The brace 20 and front leg 3 have no direct effect on the folding action, although it should be noted that the brace 20 controls the folding and extension of the front leg.

I do not herein claim the artistic design of this chair, as the same forms the subject of a separate application filed by me under date of May 18, 1927 Serial No. 22,028, patented Aug. 23, 1927, Des. 73,275.

Having thus described my invention what I claim as new and desire to secure by Letters Patent is:

1. In a chair structure, a frame comprising back legs, a folding seat pivoted to the back legs, a yieldable brace between the back legs, an oblique brace slidably connected at one end to the seat and pivoted at its opposite end to the yieldable brace, said oblique brace being deflected intermediate its ends to provide an end adapted to cross behind the dead center position of the seat in the chair structure whereby to automatically lock the seat in folded position.

2. In a chair structure, a main frame comprising back legs, a seat pivotally mounted between said legs to swing behind the plane of the back legs, a front leg having a forked end pivotally connected with the seat at spaced points remote from the seat pivots whereby a firm front leg attachment is accomplished, an oblique brace slidably mounted at one end to the seat and yieldably pivoted at its opposite end to the main frame, and a horizontal brace pivoted at one end to the front leg and at its opposed end to the frame.

3. In a chair structure, a frame comprising back legs, a foldable seat pivotally mounted between the back legs to swing upwardly therebetween from open to closed position, an oblique brace pivoted to the frame at one end and connected to the seat at its other end, said oblique brace being deflected intermediate its ends to permit said end connected to the seat to extend behind the dead center position of the seat with respect to the back legs when the same is folded, and a yieldable connection between said brace and the chair frame comprising an arched brace connecting the back legs of the chair.

4. In a metal chair construction, a frame forming back legs and a seat pivotally mounted between the back legs to swing therebetween, a yieldable brace between the back legs, a pivoted oblique brace extending between the seat and said yieldable brace, a front leg pivoted to the seat and a pivoted horizontal brace connecting said front leg and said frame, said oblique brace having a sliding pivotal connection with the seat at one end and a connection at its opposite end with the yieldable brace, and being deflected intermediate its ends to permit the slidably connected end thereof to extend behind the dead center position of the seat when the same is in raised position.

5. In a metal chair construction, a frame forming back legs and a back rest formed as a continuation of the back legs, a seat pivotally mounted between the back legs to swing therebetween, a yieldable brace between the back legs, a pivoted oblique brace extending between the seat and said yieldable brace, a front leg pivoted to the seat and a pivoted horizontal brace connecting said front leg with the frame, said oblique brace having a sliding pivotal connection with the seat at one end and pivotally connected at its opposite end to the yieldable brace, said oblique brace being deflected from a straight line between its ends to permit one end to cross behind the dead center position of the seat when the same is in raised position, and co-

operating means on the seat and the sliding connection for locking the seat in extended position.

6. In a metal chair construction, a frame forming back legs and a back rest, a seat pivoted between the back legs to swing therebetween, a yieldable brace connecting the back legs, an oblique brace pivoted at one end to said yieldable brace, and having a sliding pivotal connection at its other end with the seat, said oblique brace being deflected from a straight line intermediate its ends to permit the end which is connected to the seat to cross the dead center position of the seat when the same is moved to folded position, and cooperating means formed on the seat and on the sliding connection for locking the seat in open position, said means comprising a spring pressed latch mounted on the seat and adapted to lockingly engage a latch keeper formed in the sliding connection.

7. A substantially all-metal chair comprising a tubular rod-like member bent to form a pair of spaced back legs and a back rest as a continuation thereof, a seat pivoted between the back legs to swing into a folded position substantially parallel with the back rest, a yieldable brace secured between the back legs, an oblique brace having a sliding connection with the seat and a pivoted connection with the said yieldable brace, a single front leg pivoted to the seat, at spaced points to provide a firm pivotal connection, and a horizontal brace pivoted to said yieldable brace and the front leg.

8. A substantially all-metal chair comprising a tubular rod-like member bent to form a pair of spaced back legs and a back rest as a continuation thereof, a seat pivoted between the back legs to swing into folded position substantially parallel with the back rest, a yieldable brace secured between the back legs, an oblique brace having a sliding connection with the seat and a pivoted connection with the said yieldable brace, a single front leg having forked branches pivoted to the seat, and a horizontal brace pivoted to said yieldable brace and the front leg, all of said pivoted braces including the front leg being deflected from a straight line between their respective ends so as to fold with the seat in closely nested relation in the frame.

9. A seat pivotally mounted to swing upward, a brace for the seat, a block-like member to which the brace is pivoted, means on the seat for slidably mounting said block-like member, and means on the seat for releasably engaging said member at the limit of its forward movement for locking the seat in its extended position, comprising a spring-pressed latch positioned to automatically engage the block-like member and having a lip arranged to ride over a projection on said member and seat behind the same.

10. A seat pivotally mounted to swing upward, a brace for the seat, a block-like member to which the brace is pivoted, means on the seat for slidably mounting said block-like member, and means on the seat for releasably engaging said member at the limit of its forward movement for locking the seat in its extended position, comprising a spring-pressed latch positioned to automatically engage the block-like member and having a lip arranged to ride over a projection on said member and seat behind the same, the seat having a front supporting leg with forked branches on the leg pivoted to the seat, and said latch having an actuating end positioned between said forked branches.

11. In a chair construction, a main frame comprising back legs, a seat pivoted between said legs to fold upwardly therebetween, a front leg having a forked end pivotally connected to the seat whereby a firm attachment is accomplished, an oblique brace slidably mounted at one end to the seat and yieldably pivoted at its opposite end to the main frame, and a horizontal brace pivoted at one end to the front leg and at its opposite end to the frame below the pivoted end of the oblique brace whereby, when the seat is in folded position, the front leg may be closely folded substantially parallel with the seat and frame.

12. A folding chair having a main frame, a seat pivoted in the frame, an oblique brace slidably connected at one end to the seat, and at the other end pivotally connected to the main frame, a forked front leg having spaced portions pivotally connected to the seat at spaced portions whereby a firm front leg connection is accomplished, and a brace pivoted to the main frame and to the front leg below the forked portion.

13. A folding chair having a main frame providing a resilient portion, a seat pivoted in said frame to swing therein between open and folded position, and an oblique brace pivoted at its lower end to the resilient portion of the frame, said brace having, at its upper end, a sliding connection with the seat, a stop so positioned on the seat as to limit the sliding movement of the upper end of the brace when in line with the seat and brace pivots whereby to tension the resilient portion of the frame, the sliding end of the brace extending behind the seat and brace pivots when the seat is in folded position.

14. A folding chair having a main frame forming a back rest and legs, a seat pivoted in said frame to swing up and down therein and an oblique brace pivoted at one end to a resilient portion of the frame and having at its upper end a sliding connection with the seat, a stop on the seat so positioned as to limit the sliding movement of the upper end of the brace with respect to the seat when in line with the seat and brace pivots, the brace

being off-set whereby its sliding end extends behind the plane defined by the points about which the seat and the said brace are pivoted in the frame.

5 In witness whereof, I have hereunto subscribed my name.

JOHN B. ADLER.
